UNITED STATES PATENT OFFICE.

STEPHEN FAITH AND EDMORE N. BOUCHER, OF CHICAGO, ILLINOIS.

CARD-INDEX.

1,367,030.

Specification of Letters Patent.

Patented Feb. 1, 1921.

Application filed December 6, 1919. Serial No. 342,920.

To all whom it may concern:

Be it known that we, STEPHEN FAITH and EDMORE N. BOUCHER, citizens of the United States, and residents of the city of Chicago, in the county of Cook and State of Illinois, have invented certain new and useful Improvements in Card-Indexes; and we do hereby declare that the following is a full, clear, and exact description of the same, reference being had to the accompanying drawings, and to the numerals of reference marked thereon, which form a part of this specification.

This invention relates to an improved type of a selectively operated classified card index, wherein key operated ejecting levers are adapted to be operated to elevate cards into a visible position.

It is an object of this invention to provide a selective card index.

It is also an object of the invention to provide a key operated card index.

Another object of the invention is the construction of an index wherein classified cards may be selectively projected from a card case.

A further object of the invention is the construction of a card index wherein key operated levers are adapted to be selectively operated to raise notched index cards out of pockets provided in the card index casing.

It is an important object of this invention to provide a simple and effective card index wherein the cards are engaged with hooked key operated levers to permit any one or plurality of cards to be projected from the index casing.

Other and further important objects of this invention will be apparent from the disclosures in the drawings and specification.

The invention (in a preferred form) is illustrated in the drawings and hereinafter more fully described.

On the drawings:

Figure 1 is a side elevation of a card index embodying the principles of this invention.

Fig. 2 is a top plan view thereof.

Fig. 3 is a front end view of the device.

Fig. 4 is a sectional view taken on line 4-4 of Fig. 2 showing one of the cards in elevated position.

Fig. 5 is a section taken on line 5-5 of Fig. 4.

Fig. 6 is an enlarged bottom plan view of one of the keys taken on line 6-6 of Fig. 1.

Fig. 7 is a detail section taken on line 7-7 of Fig. 6.

Fig. 8 is an enlarged fragmentary detail view taken on line 8-8 of Fig. 4.

Fig. 9 is a section taken on line 9-9 of Fig. 8 with parts in elevation.

Fig. 10 is an enlarged fragmentary detail section taken on line 10-10 of Fig. 4.

As shown on the drawings

The card index comprises a box or casing embracing a bottom 1, a rear wall 2, side walls 3 and 4, an upper front wall 5, and a lower front wall 6. The upper front corners of the side walls 3 and 4, are cut away to permit a key board or plate 7 to be rigidly secured in position to close the front reduced portion of the casing. The plate 7 is provided with a plurality of slots or openings 8 arranged in offset rows.

Struck from the high portion of the side wall 3 are two vertical angle strips or guides 9 adapted to permit a calendar 10 or memorandum cards to be held in place as shown in Fig. 1. Also provided on the sidewall 3 and near the lower portion thereof is a horizontal pencil holder 11 adapted to hold a pencil 12 seated therein. As clearly shown in Fig. 4, the upper front wall extends below the key board plate 7 and is provided with an integral flange 13. Rigidly secured to the flange 13 and to the side walls of the casing is a horizontal guide plate or partition 14 provided with a plurality of slots or openings 15 disposed directly below the slots 8 in the plate 7.

The operating mechanisms are mounted within the front chamber 16 of the casing and project into the rear or card chamber 17 of said casing. Securely mounted within the card chamber 16 parallel to and spaced a short distance in front of the rear wall 2 is a plate 18 the upper margin of which is bent rearwardly at right angles to form a flange 19 which is secured to the upper edge of said rear wall. The plate 18 and the flange 19 thereof are cut or stamped to afford a plurality of parallel card guide slots 20. Also rigidly secured transversely in the card chamber 17 and substantially midway between the rear wall 2 and the upper front wall 5 is a plate 21 the upper portion of

which is bent forwardly at right angles to form a top flange plate 22, the front edge of which is secured to the upper edge of the upper front wall 5. The plate 21 and the flange plate 22 thereof are cut or stamped to afford a plurality of parallel vertical slots 24 which register with each other. The slots 23 and 24 are disposed opposite the slots 20 to afford suitable guide ways for receiving 10 index cards 25. The lower margin of each of the index cards 25 is cut to provide a recess 26 having a notch 27 forming a part thereof.

Mounted transversely within the chamber 16 below the partition guide plate 14 are a plurality of parallel horizontal rods or shafts 28. Pivotally mounted on each shaft 28 are a plurality of card ejectors each comprising a short arm 29 and a long arm 30 20 integrally connected at right angles to each other. The long arm 30 of each ejector projects into the card chamber 17 and has an upwardly directed hook 31 integrally formed at the end thereof. The end of the short 25 ejector arm 29 is engaged on its respective shaft 28. Integrally formed on the end of each short ejector arm 29 is a stop 32 and a finger or lug 33 positioned at right angles to each other. Each of the long ejector arms 30 is disposed to lie underneath one of the index cards 25 with the ejector hook positioned to engage in the card recess 26.

An independently operable mechanism is provided for each of the card ejectors. Each 35 of said mechanisms comprises a key or button 34 provided with a name plate 35 secured between a transparent covering 36 and back plate 37. The covering 36, the name plate 35, and the back plate 37 are held in place 40 within the key 34 by retaining lugs 38. Each key 34 is supported by a stem or holder 39 which projects downwardly through one of the keyboard slots 8 and the slot 15 directly 45 therebelow in the plate 14. The lower end of each key stem 39 is provided with a slot 40 to permit the key stem to engage over one of the ejector lugs 33, as shown in Fig. 9.

The operation is as follows:

The card index is portable and may be 50 constructed of wood or metal, or a combination of both. As shown in Fig. 1, the casing is arranged to permit a calendar 10 or, if desired, memorandum slips or cards, to be carried by the holders 9, so that notations 55 may be readily made with a pencil carried by the holder 11.

The index cards 25 are first properly classified and then deposited in the respective slots 20—23—24, so that the lower edges 60 thereof will be positioned above the long arms 30 of the ejectors. The hooks 31 of the ejectors are adapted to project into the card recesses 26 to support the cards within the card chamber 17.

65 As disclosed in Fig. 2, the keys are let-

tered alphabetically and are arranged with the keys in one row offset or staggered with respect to those in another row. Any suitable key name plates may be used other than those bearing letters.

To elevate or eject a certain card 25 from the index casing the corresponding key 34 is manually depressed thereby causing the key stem 39 to slide downwardly through the guide slots 8 and 15. The downward movement of the key stem 39 acts to swing the ejector finger 33 downwardly and thereby cause the respective ejector 29—30 to swing upwardly as shown in Fig. 4, until the ejector stop 32 contacts the under surface of the plate 14, thus limiting the upward swing of the ejector. Upward movement of an ejector arm 30 causes the hook 31 thereof to elevate the index card 25 resting thereon. With the elevation of a card 25, the hook 31 moves in the recess 26 thereof and engages in the notch 27, thereby holding the elevated card to prevent complete ejection thereof from the card chamber 17. Upon release of a key 34 the weight of the card 25 and the ejector act as a counter-weight to automatically elevate the key 34 to its normal elevated position.

If desired the card slots may be made wider to hold a plurality of cards, all of which may be elevated by simply depressing a single key. A number of keys 34 may be operated at the same time to cause a plurality of cards to be elevated if desired. The designations on the key name plates permit a selective operation to be conveniently made of the cards contained within the index casing. A card may be readily removed from its normal position or when only partly elevated and before the ejector hook engages in the card notch 27.

We are aware that numerous details of construction may be varied through a wide range without departing from the principles of this invention, and we therefore do not 11 purpose limiting the patent granted otherwise than necessitated by the prior art.

We claim as our invention:

1. A card index comprising a casing having guide slots therein for holding a notched 11 card, an ejector pivotally mounted within the casing, a hook thereon for engaging in the notch of said card, a finger on said ejector, a key, a slotted stem secured to said key and engaged on said finger to permit said 12 ejector to swing upwardly to elevate the card when the key is depressed, and a stop integrally formed on the pivoted end of said ejector for limiting the upward movement of said ejector and card.

2. A card index comprising a casing having guide slots therein for receiving index cards, said cards having notches therein, ejectors in said casing for elevating said cards, keys for operating said ejectors, and 130

hooks on said ejectors adapted to engage in the card notches to hold the cards locked against complete ejection when elevated.

3. A card index comprising a casing having card guide slots therein, slotted guide plates forming a part of said casing, keys positioned above said plates, slotted stems secured to said keys and projecting downwardly through the slots in said plates, ejectors pivotally mounted in said casing, means integrally formed thereon adapted to be engaged by the key stems, stops formed on said ejectors for limiting the movement

thereof, and means also formed on said ejectors for engaging cards in said casing to permit elevation of said cards when said keys are depressed.

In testimony whereof we have hereunto subscribed our names in the presence of two subscribing witnesses.
